UNITED STATES PATENT OFFICE.

SAMUEL S. MATTHES, OF MANSFIELD, OHIO, ASSIGNOR TO THE OHIO BRASS COMPANY,
OF MANSFIELD, OHIO, A CORPORATION OF NEW JERSEY.

ELECTRIC-CURRENT-COLLECTING DEVICE.

1,416,045.

Specification of Letters Patent. Patented May 16, 1922.

Application filed October 17, 1921. Serial No. 508,120.

To all whom it may concern:

Be it known that I, SAMUEL S. MATTHES, a citizen of the United States of America, residing at Mansfield, in the county of Rich-
5 land and State of Ohio, have invented cer-
tain new and useful Improvements in Elec-
tric - Current - Collecting Devices, of which
the following is a specification.

My invention relates to a current collect-
10 ing device and particularly to that class
which is applicable to use with a car or bus
operated without the use of tracks and
known as trackless trolley operation.

It has for its object a device which will
15 collect current from a plurality of overhead
conductors of different polarity; to be so
mounted on the trolley pole or other support
as to adjust itself to variations in the rel-
ative height of the trolley conductors and
20 movement or swing of the bus from the cen-
ter line of the conductors to either side there-
of; to maintain itself in substantial aline-
ment with the trolley conductors under all
conditions.

25 In the accompanying drawing:—

Fig. 1 is a top plan view of my device se-
cured to a supporting pole.

Fig. 2 is a side elevation of Fig. 1.

Fig. 3 is a detail of the connecting means
30 for mounting the head on the pole or sup-
port.

In my preferred construction I employ a
pole or support 1, which is of the ordinary
well known types now in use, upwardly-
35 spring-pressed and mounted, at the lower
end, to the bus by any well known trolley
base. Mounted on the support 1 is the head
H involving my invention. The head com-
prises a triangularly shaped frame compris-
40 ing the arms 2—2 and 3. The arms 2—2 are
secured together through adjacent ends by
the members 4—4 which are anchored in
place by rivets, bolts or screws 5. Projecting
45 from the members 4 and shown as integral
therewith are studs 6 upon which are mounted
the contactors 7—7 shown as revolving wheels
but which may be of the sliding or shoe type.
Also pivotally mounted on one of the studs
50 4 and the arm 3 is a trailer or alining mem-
ber. A spring 9 holds the member 8 in an
upwardly pressed direction. The arm 3 is
shown as of wood in order to electrically in-
sulate the members 7—7 from each other and
the arms 2—2 are also shown as of wood to

insulate the members 7—7 and 8 from the 55
pole 1. The insulation between the mem-
bers 7—7, 8 and 1 may be of other material
than wood or of other construction, but it is
necessary, obviously, to insulate these parts
from each other in some manner. Secured 60
to the member 8 by the pin 10 and cotters 11
is a wheel contactor 12 which may also be
of the sliding shoe type.

The construction above described is mount-
ed on the support 1 by means of the mount- 65
ing M which also serves to hold the lower
ends of the arms 2—2 in position by the bolts
13. The mounting comprises a member 14
having a recess 15 to receive the end of the
support 1 to which it is held by the pins 16 70
and a recess 17 in which the member 18 is
pivotally mounted. The member 18 is pro-
vided with a stud 19 fitting the recess 17 and
held in place by the nut 20 and is also pro-
vided with a plate 21. The plate 21 is 75
notched at 22 and the sides of the notch en-
gage a pin 23 which limits the amount of
pivotal action of the member 18 relative to
the member 14.

80 The member 18 is provided with a pro-
jecting stud 24 which fits a recess 25 in the
member 26. The member 26 is provided with
a notch 27, the sides of which engage a pin
28 on the member 18 and a nut 29 holds the
members 26 in position on the stud 14. 85

There are many variations in the detailed
disclosure described above and shown in
the drawings which will be evident to those
skilled in the art and which variations will
fall within the scope of my invention. 90

It will be evident that in the operation of
my invention that the head H will be main-
tained in a predetermined alinement with
the conductors 30 regardless of the angle
which the support 1 may take with the head 95
H so long as the limit of movement between
the head H and the support 1 is not ex-
ceeded or the limit of swivel between the
members 18 and 26 is not exceeded. The ten-
sion of the spring 9 is less than the tension 100
in the spring maintaining the support 1 in
a raised position with the contactors in
engagement with the conductor thereby
avoiding forcing either of the members 7—7
off its conductor. 105

What I claim is:—

1. A collector for electric currents com-
prising in combination a support member

and a head mounted on the support member in rotatable and pivotal relation thereto, the head comprising a triangular shaped member having a contacting member at each 5 of two of its corners and the third corner adjacent the support member, and having the contacting members insulated from each other and a trailing member at one corner of the triangular member to engage a trolley 10 wire and maintain the head in alinement with the trolley wire.

2. A current collector comprising in combination a support member and a head mounted on the support in rotatable and 15 pivotal relation thereto, the head comprising a pair of spaced and insulated contactors to engage conductors and insulated from the support, and a contacting member arranged to engage one of the conductors to 20 maintain the head in alinement with the conductors.

3. A current collector comprising in combination a support member and a head mounted on the support, the head provided 25 with a plurality of contactors each to engage a conductor and spaced and insulated from each other and from the support, and provided with means to engage one of the conductors to maintain the head in alinement 30 with the conductors.

4. A current collector comprising in combination a support member and a head mounted on the support, the head provided with a plurality of contactors each to engage 35 a conductor and spaced and insulated from each other and from the support, and provided with means pivotally mounted on the head to engage one of the conductors to maintain the head in alinement with the conductors.

5. A current collector comprising in combination a support member and a head mounted on the support, the head provided with a plurality of contactors each to engage 45 a conductor and spaced and insulated from each other and from the support, and provided with spring-held means pivotally mounted on the head to engage one of the conductors to maintain the head in alinement with the conductors.

6. A current collector comprising in combination a support member and a head mounted on the support, the head provided with a plurality of contactors each to engage 55 a conductor and spaced and insulated from each other and from the support, and provided with upwardly-spring-held means pivotally mounted on the head to engage one of the conductors to maintain the head in alinement with the conductors.

7. A current collector comprising in combination a support member and a head mounted on the support, the head provided with a contactor adapted to engage a conductor and insulated from the support, and 65

means pivotally mounted on the head in line with the contactor to maintain the head in alinement with the conductor.

8. A current collector comprising in combination a support member and a head 70 rotatably mounted on the support, the head provided with a contactor adapted to engage a conductor and insulated from the support, and means pivotally mounted on the head in line with the contactor to maintain the head 75 in alinement with the conductor.

9. A current collector comprising in combination a support member and a head pivotally mounted on the support, the head provided with a contactor adapted to engage a 80 conductor and insulated from the support, and means pivotally mounted on the head in line with the contactor to maintain the head in alinement with the conductor.

10. A current collector comprising in combination a support member and a head pivotally and rotatably mounted on the support, the head provided with a plurality of contactors each to engage a conductor and spaced and insulated from each other and from the support, and provided with means to engage one of the conductors to maintain the head in alinement with the conductors, and means to limit the amount of pivotal and rotatable motion. 95

11. A current collector comprising in combination a plurality of contactors each to engage a conductor, means supporting, spacing and insulating the contactors, means to support the contactors from a moving vehicle, means for securing to and insulating the contactors from the support in pivotal and rotatable relation thereto, means to maintain the contactors in alinement with the conductors and means to limit the pivotal 100 and rotatable movement.

12. A current collector comprising in combination a support member and a head mounted on the support, the head provided with a plurality of contactors each to engage 110 a conductor and spaced from each other and from the support, and provided with means to engage one of the conductors to maintain the head in alinement with the conductors.

13. A current collector comprising in combination a support member and a head mounted on the support, the head provided with a plurality of contactors each to engage a conductor and spaced and insulated from each other and mounted to rotate relatively to the support, and provided with means to engage one of the conductors to maintain the head in alinement with the conductors. 115

14. A current collector comprising in combination a support member and a head mounted on the support, the head provided with a plurality of contactors each to engage a conductor and spaced and insulated from each other and mounted to pivot relatively 120 125 130

to the support, and provided with means to engage one of the conductors to maintain the head in alinement with the conductors.

15. A current collector comprising in combination a support member and a cross-head thereon mounted for universal movement, the cross-head provided with a plurality of contactors each to engage a conductor and

spaced and insulated from each other and from the support, and provided with means to engage one of the conductors to maintain the cross-head in alinement with the conductors.

In testimony whereof I affix my signature.

SAMUEL S. MATTHES.
